UNITED STATES PATENT OFFICE.

ARTHUR F. DERSE, OF UNION COURSE, AND WILLIAM B. WILSHUSEN, OF MOUNT VERNON, NEW YORK.

COMBINED CASE AND TABLE.

1,357,623.

Specification of Letters Patent.

Patented Nov. 2, 1920.

Application filed December 16, 1919. Serial No. 345,314.

To all whom it may concern:

Be it known that we, ARTHUR F. DERSE, a citizen of the United States, and a resident of Union Course, in the county of Queens and State of New York, and WILLIAM B. WILSHUSEN, a citizen of the United States, and a resident of Mount Vernon, in the county of Westchester and State of New York, have invented a new and useful Combined Case and Table, of which the following is a specification.

The present invention relates to a combination case and table and has for its main object to provide a case in which a table is adapted to fold in such a manner as to afford a central space for the reception of a luncheon kit, or the like, the case forming a center support for the table when open.

The invention consists of the foregoing and other features of construction hereinafter described in connection with the preferred embodiment of the invention herein disclosed, from which embodiment, however, changes may be made without departing from the legitimate and intended scope of the invention as expressed in the appended claims.

In the drawings:

Figure 1 is a plan view of the table when set up.

Fig. 2 is a plan view of one of the chairs.

Fig. 3 is a side elevation of the table in set-up position.

Fig. 4 is a view in elevation of one of the chairs in folded position.

Fig. 5 is a vertical sectional view through the case showing the table nested within.

Fig. 6 is a fragmentary perspective view of one of the table legs and leaves.

Fig. 7 is a view similar to Fig. 5 with parts broken away showing the table open.

Fig. 8 is a top plan view of the open case with table nested and with parts broken away and in section.

Fig. 9 is a detail sectional view on the line 9—9 of Fig. 7.

1 is a case a little longer than a dress suit case provided with an open top 2 having a hinged cover. The table consists of a center leaf or section 3 to which are pivotally connected foldable leaves or sections 4 and 5 having grasping portions 6.

Legs 7 and 8 provided with arms or extensions 7' and 8' respectively are pivotally connected to leaves 4 and 5 and are also piv-

otally connected to links 9 and 10 which in turn swing on pivots 11 carried by sides of leaf 3.

Leaf 3 is provided at each end with a traveler 17 which slides upon guides 12 and 13 which are stationary with the case.

The guides are supported at the top of the case by plates 18 which serve as stops against which the travelers 17 on the leaf 3 abut on upward movement of said leaf to prevent its withdrawal from the case.

When it is desired to open the table (see Fig. 5) cover 2 is swung to one side and the handles 6 are lifted. The parts are brought straight up out of the case, leaf 3 sliding on guides 12 and 13 until it strikes stops 18. The leaves 4 and 5 are then lowered into a horizontal position, the links 9 and 10 swinging on pivots 11 acting to automatically swing the legs 7 and 8 on their pivots to an upstanding position as the leaves are lowered. By reason of the connection between the case and the center leaf, the table is very rigidly supported by the case and the legs.

When it is desired to fold the table (table occupying position in Fig. 3) handles 6 are lifted. Leaves 4 and 5 will swing on their pivots and links 9 and 10 will act on legs 7 and 8 to cause them to fold against the leaves 4 and 5. When parts 4, 5, 7 and 8 are parallel above the case, they are pushed down until they occupy the position shown in Fig. 5. It will be noted here that leaf 3 is at the bottom and leaves 4 and 5 are adjacent the sides of the case. Cover 2 may then be closed.

It is observed that the links 9 and 10 not only act automatically to fold and unfold the legs as the table is folded or unfolded but also hold the legs and restrain them from swinging back and forth at random when the operation of folding or unfolding the table is taking place.

When the table is nested as in Fig. 5, a central space is afforded in which may be placed a lunch kit, plates, thermos bottles, knives, forks, etc. This is indicated by the container shown by dotted lines 14.

Foldable chairs may also be placed in this space. Each chair consists of two rectangular frames 15—16 pivoted together and connected at their upper ends by canvas. Two of these chairs are shown nested at the bottom in Fig. 5.

We claim:

1. A combination case and table comprising: a casing having an open top, a central table leaf horizontally disposed and slidable vertically within the casing from a position adjacent the bottom to a position adjacent the top of the casing, two foldable leaves pivotally connected to the central leaf, said foldable leaves being, when they occupy a vertical position above the central leaf, slidable into and out of the casing, and forming, when horizontally disposed, continuations of the central leaf when the latter is in its upper position; and legs, pivotally connected to the foldable leaves, occupying a vertical position parallel to said leaves when the latter are in a vertical position to slide into and out of the casing with said leaves, said legs also occupying a vertical position to support the foldable leaves when the latter are horizontally disposed.
2. A combination case and table comprising: a casing having an open top, a central table leaf horizontally disposed and slidable vertically within the casing from a position adjacent the bottom to a position adjacent the top of the casing, and two foldable leaves pivotally connected to the central leaf, said foldable leaves being, when they occupy a vertical position above the central leaf and on either side thereof, slidable into and out of the casing adjacent the side walls thereof, the three leaves affording, when nested within the casing, an intervening space between them for the reception of a container or the like, and said foldable leaves forming, when horizontally disposed, continuations of the central leaf when the latter is in its upper position and legs pivotally connected to the foldable leaves, occupying a vertical position parallel to said leaves when the latter are in a vertical position to slide into and out of the casing with said leaves between the latter and the former, said legs also occupying a vertical position to support the foldable leaves when the latter are horizontally disposed.
3. A combination case and table comprising:

ing: a casing having an open top, a central table leaf horizontally disposed and slidable vertically within the casing from a position adjacent the bottom to a position adjacent the top of the casing, and two foldable leaves pivotally connected to the central leaf, said foldable leaves being, when they occupy a vertical position above the central leaf and on either side thereof, slidable into and out of the casing adjacent the side walls thereof, the three leaves affording, when nested within the casing, an intervening space between them for the reception of a container or the like, and said foldable leaves forming, when horizontally disposed, continuations of the central leaf when the latter is in its upper position and legs pivotally connected to the foldable leaves, occupying a vertical position parallel to said leaves when the latter are in a vertical position to slide into and out of the casing with said leaves between the latter and the former, said legs also occupying a vertical position to support the foldable leaves when the latter are horizontally disposed.

4. A combination case and table comprising: a casing having an open top, a central table leaf horizontally disposed and slidable vertically within the casing from a position adjacent the bottom to a position adjacent the top of the casing, two foldable leaves hinged to the center leaf, foldable legs pivotally connected to the foldable leaves, arms carried by said foldable legs and links pivotally connected to the center leaf and pivotally connected to the arms of the legs.

Signed at New York, in the county of New York and State of New York, this 3rd day of December 1919.

ARTHUR F. DERSE.
WILLIAM B. WILSHUSEN.
